COUPLING TRANSFORMER

Harold T. Lyman, Milford, Conn., assignor to General Electric Company, a corporation of New York

Application June 2, 1936, Serial No. 83,057

11 Claims. (Cl. 178—44)

My invention relates to coupling devices for electric circuits and more particularly to coupling units which are adapted to be used in coupling successive stages of an electron discharge amplifier system.

The advantages of transformer coupling in high frequency electric circuits over other forms of coupling are well known. This type of coupling is particularly advantageous in connection with electron discharge amplifiers wherein it is desirable to obtain the highest degree of undistorted amplification with a minimum number of circuit elements. However, the conventional type of coupling transformer now employed for this purpose is open to the limitation that a uniform amplification response characteristic can not be obtained over a wide band of frequencies. This limitation is due to the fact that series resonant conditions are produced in the windings of a transformer at certain frequencies which lie within the operating range and which produce attenuation of the components of current having frequencies corresponding to such series resonant frequencies. It has therefore been the practice in the past to employ resistance coupling in those circuits wherein it was desired to transmit currents having a wide band of frequencies between two electrically coupled circuits.

It is an object of my invention to provide in a high frequency circuit a transformer which is capable of transmitting between two circuits electric oscillations having component frequencies extending over a wide range with equalized transmission efficiency for all of the frequency components within the range.

It is a further object of my invention to provide a transformer having the above operating characteristics which is self-contained, which is small in size, and which is of economical construction.

In accordance with my invention, the above objects are attained by dividing the primary and secondary windings of the transformer into coil sections. These sections are designed to have different resonant frequencies and the sections of each of the two windings are so disposed on the transformer core and so connected that a high leakage reactance obtains between the respective coil sections.

Further, in accordance with my invention, the effects of series resonance between any two coil sections of either of the windings are obviated by shunting the sections having the higher resonant frequencies with resistances having values equal to the reactance values of the coil sec-

tions which they shunt at the frequency where resonance obtains between the shunted coil section and the coil section having an immediately lower resonant frequency.

A transformer constructed in accordance with my invention may be considered as comprising a plurality of frequency transmission channels, each capable of transmitting a predetermined portion of the operating frequency band. The coil sections described above included in each of these channels are so connected and so disposed about the core of the transformer that the respective channels operate substantially independently of each other and no undesired interaction between the different channels, such as loading effects, are produced. In this manner, all of the frequency components existing in the output from a source of oscillations may be impressed on any form of utilizing circuit with a uniform transmission efficiency.

The novel features which I believe to be characteristic of my invention are set forth with particularity in the appended claims. My invention itself, however, both as to its organization and the method of operation, together with further objects and advantages thereof, will best be understood by reference to the specification, taken in connection with the accompanying drawings, in which Fig. 1 illustrates a circuit having one form of my improved coupling unit included therein; Figs. 2 and 3 illustrate curves relating to the unit shown in Fig. 1; Fig. 4 illustrates a modification of the unit shown in Fig. 1; Fig. 5 illustrates a physical embodiment of my improved transformer; Fig. 6 illustrates the circuit connections for the transformer shown in Fig. 5; Figs. 7 to 13 inclusive illustrate the equivalent circuits of the coupling unit shown in Fig. 5 when different frequency bands are considered; Fig. 14 illustrates another physical embodiment of my improved transformer, and Fig. 15 illustrates the circuit connections for the transformer shown in Fig. 14.

Referring to Fig. 1 of the drawings, I have illustrated the simplest form of my improved coupling unit at 1 as a device for impressing the output from an electron discharge amplifier 2 on the input circuit of an electron discharge amplifier 3. As shown, the coupling unit 1 comprises a core 4 upon which are wound primary and secondary windings 5 and 6. The primary winding 5 is illustrated as comprising a pair of series connected sections 7 and 8 and the secondary winding 6 is comprised of a pair of series connected sections 9 and 10. In order to pre-

vent electrostatic or capacity coupling between the windings 5 and 6 an electrostatic shield 11 is provided which is maintained at ground potential.

5 In certain applications, as for example in television modulation circuits, the oscillations which it is desired to transmit between the two coupled circuits may have frequency components extending over an exceedingly wide range. Thus, the 10 discharge amplifiers 2 and 3 may form a part of an amplifying system for amplifying the signal currents generated in a circuit whose energization is controlled in response to the energization of a television pick-up device.

15 It is known that to operate satisfactorily a coupling device or coupling network between two electrically coupled circuits must be capable of transmitting between the circuits all of the frequency components of the alternating voltage 20 impressed across terminals of the coupling system with a uniform transmission efficiency. Obviously, to obtain this uniform transmission efficiency the impedance of the coupling device or network must be maintained above a certain 25 predetermined value for all of the frequency components of current flowing therein.

As will be pointed out in detail hereinafter, certain difficult problems are involved in the construction of a transformer offering the desired 30 high impedance to currents of all frequencies within a wide range. One such problem which arises in the construction of a transformer suitable for transmitting between windings currents having a wide band of frequencies is that of 35 eliminating undesired reductions in the impedance of the windings produced by series resonance effects between the inductance and distributed capacity of the windings at certain frequencies.

40 Such resonance effects may be overcome by dividing the primary and secondary windings into sections having different resonant frequency characteristics thereby to provide a plurality of channels for the transmission of energy between 45 the two coupled circuits. Thus the sections 8 and 10 and the coupling therebetween may be considered as comprising one channel of the coupling device of Fig. 1, and the inductively related sections 7 and 9 may be considered as the other 50 channel. By dividing the windings in this manner each of the inductively related pairs of sections may be designed to transmit a particular portion of the operating frequency range. For example, the winding sections 8 and 10 may each 55 comprise a small number of turns as compared to the number of turns in the sections 7 and 9 respectively, and may be designed to have a very low distributed capacity and a higher resonant frequency than that of the sections 7 and 9. As 60 thus constructed, these inductively related sections operate to transfer between the two amplifier stages the high frequency components of the oscillations generated in the output circuit of the amplifier 2 and the relatively larger sections 65 7 and 9 operate to transfer the low frequency components of the oscillations.

One difficulty encountered in utilizing this 70 multi-channel method of coupling is that produced by resonance effects occurring between the reactances of the coil sections at certain frequencies within the operating frequency range. These resonance effects reduce the effective impedance of the coupling device at certain frequencies to such an extent that the transmission

of currents having these frequencies may be materially reduced or completely prevented.

The effect of resonance between the reactance of the winding sections to reduce the impedance between the terminals of the windings to currents of certain frequencies may more clearly be understood by reference to Fig. 2 wherein the impedance characteristics of the winding sections 7 and 8 of the primary winding 5 are plotted as a function of frequency, assuming no 10 load conditions of the transformer. In this figure, the curves 12 and 13 represent the calculated internal inductive reactances of the winding sections 7 and 8 respectively as a function of frequency and the curves 14 and 15 illustrate the 15 apparent external reactance of the same circuit elements including the effects of distributed capacity of these elements. The curves 16 and 17 show the apparent resistances of the windings 7 and 8 for the various frequencies within the 20 operating range.

It will be observed that due to the distributed capacity of the coil section 7, this coil is in a resonant condition at a frequency F_1 and at higher frequencies it is at first increasingly capacitively reactive and later decreasingly capacitively reactive. This capacitive reactance is sufficient at frequencies F_2 (slightly higher than frequency F_1) and F_3 to form a series resonant circuit with the inductive reactance of the section 8. However, at the frequency F_2 , the apparent resistance of the section 7, as shown by curve 16, is sufficient to maintain the impedance between the terminals of the primary winding 5 above that 30 predetermined value below which the source of 35 impressed voltage is overloaded. At F_3 , however, the apparent resistance of the winding 7 is negligible and the series resonance produced between the reactances of the sections 7 and 8 reduces substantially to zero the overall impedances of 40 the primary windings to currents of these frequencies. Hence, at this frequency, F_3 , and in the absence of additional means for maintaining the overall terminal impedance above the predetermined value necessary to produce equalized 45 transmission efficiency, substantially no transfer of energy having this frequency will occur between the primary and secondary windings.

In order to obviate the above difficulty and provide the necessary impedance in the intermediate frequency zone at which neither of the windings 7 or 8 is otherwise effective to transmit energy, the resistance 18 is provided in shunt with the primary winding section 8.

At the frequency of resonance between the 55 reactances of the windings 7 and 8 the resistance 18 should be very low in order to prevent series resonance. However, if such a value of resistance be employed, substantially the entire effective primary section would be short-circuited 60 at frequencies above this series resonant frequency. Accordingly, it has been found desirable to use a compromised value of resistance 65 18, the value being determined to be equal to the inductive reactance of the winding section 8 at the resonant frequency where this inductive reactance is equal to the apparent capacitive reactance of the winding section 7.

The presence of distributed capacity in and 70 load across the secondary windings 9 and 10 affects the apparent reactances of the primary windings to the extent that the resonant frequencies F_1 and F_4 are shifted slightly toward decreasing frequency and furthermore the peak values of apparent reactances and resistances 75

may be reduced, but in general the relations expressed above between the values of the primary circuit constants remain substantially unchanged.

5 With the resistance 18 connected in shunt with the winding 8 and having the value designated above, the impedance characteristic of the primary winding as a function of frequency is as shown by curve 19 of Fig. 3. This curve shows 10 that the overall impedance between the terminals of the primary winding does not decrease below a predetermined minimum value at any frequency up to the resonant frequency F_4 of the winding 8. The curve further shows that at low 15 frequencies the greater portion of the impedance between the terminals of the primary winding is due to the impedance of the winding section 7 and at high frequencies the impedance of the winding section 8 is predominant. At the intermediate 20 frequencies where the reactance of the winding 7 is partially or totally in series resonance with the inductive reactance of the winding 8, the impedance between the primary winding terminals is due almost entirely to the apparent 25 resistance of the shunt resistor 18 in parallel with winding 8.

As shown by curve 19 of Fig. 3, if the winding sections 7 and 8 be constructed in the manner described above and the resistance 18 be provided in shunt with the section 8, the impedance is sufficient to transmit currents having all frequencies less than a frequency slightly higher than the resonant frequency of the high frequency winding 8.

35 Although I have described only the effects of series resonance in the primary winding, it will, of course, be understood that these effects also occur in the secondary winding and, accordingly, it is desirable to provide resistors connected in shunt with each of the secondary winding sections for the purpose of preventing series resonance effects between the winding sections from lowering the impedance of the winding to currents having 45 frequencies corresponding to the frequencies at which such resonance effects occur. The value of these resistors is determined in accordance with the principles discussed above in connection with the primary section shunting resistance. 50 Thus, in the two section secondary winding of the device illustrated in Fig. 1 a resistor 20 is provided having a value equal to the inductive reactance of the winding section 10 at the frequency where resonance obtains between this 55 reactance and the apparent capacitive reactance of the section 9, inclusive of effects on this reactance of such coupling as may exist between all windings.

The frequency range may be extended by adding 60 additional winding sections having resonant frequencies increasingly higher than that of the high frequency sections 8 and 10 and shunting each of these sections with a resistance having a value equal to the inductive reactance which it shunts at the frequency of resonance of the reactance of this winding with the reactance of the next lower resonant frequency winding section.

Thus, in Fig. 4, I have illustrated a transformer constructed in accordance with the principles outlined above in which three channels are provided for transmitting the low, intermediate and high frequency portions of the frequency band between the two windings. This 75 transformer is illustrated as including primary

winding sections 21, 22 and 23 and secondary winding sections 24, 25 and 26, the sections being so designed that the inductively coupled sections 21 and 24 constitute the low frequency transmitting channel, the sections 22 and 25 5 constitute the intermediate frequency transmitting channel, and the sections 23 and 26 constitute the high frequency transmitting channel. Each of the higher resonant frequency sections 22, 23, 25 and 26 is shunted by a resistor having a value determined in the manner set forth above. It will, of course, be understood that in practice additional frequency channels may be provided by increasing the number of winding sections and providing additional shunt resistors. 10 15

In the construction of a transformer wherein all of the inductively coupled coil sections constituting the various frequency transmitting channels are mounted upon the same core, it is necessary, if satisfactory operation is to be obtained, 20 so to arrange the sections of each winding that a considerable leakage reactance is obtained between the respective sections of the primary and secondary windings. This necessity arises from the fact that the low capacity reactance of certain of the windings may constitute a heavy load on the other windings if the winding sections are in closely coupled inductive relation. 25

In accordance with my invention, the above difficulty is obviated by mounting the winding sections on the transformer core in the manner illustrated in Fig. 5 and connecting the elements of the coupling unit in accordance with the circuit shown in Fig. 6 wherein elements identical to those of Fig. 5 are identified by like reference 35 characters.

Referring to Fig. 5 of the drawings I have illustrated the transformer as comprising a core 27 upon which are mounted primary winding sections 28, 29 and 30, and secondary winding sections 31, 32, 33, 34 and 35. The primary winding section 28 and the secondary section 31 are arranged in closely coupled inductive relation upon the center leg of the core and constitute the channel for transmitting currents having frequencies extending over the low portion of the operating frequency range. The high frequency transmitting channels are comprised of the primary sections 29 and 30 and the secondary sections 32, 33, 34 and 35. It will be observed that 40 the winding sections included in the high frequency channels are mounted on the outer legs of the three-legged core 27 thereby to provide a high leakage reactance between these winding sections and the sections of the low frequency 45 channel.

As will be more clearly brought out herein-after the respective primary winding sections are connected in such a manner that when the respective winding sections are energized the 60 sections of the high frequency channels including the primary winding sections 29 and 30 are magnetically isolated. Thus, the windings are connected in such manner that when the primary winding 28 is energized a flux ϕ_1 indicated by 65 the dash lines is produced in the core which traverses the core in the direction indicated by the arrows appended to the identified dash lines. Similarly the winding sections 29 and 30 are connected so that when they are energized a flux 70 ϕ_2 is produced in the core having the direction indicated. It will be observed that the two fluxes ϕ_1 and ϕ_2 traverse the core in such a direction that the voltage induced in the sections 29, 30, 32 and 33 are opposite and, hence, the two high frequency 75

quency windings 29, 32 and 30, 33 are in effect magnetically isolated from the windings 28 and 31. The secondary winding sections 34 and 35 are connected so that the flux ϕ_1 induces equal and aiding voltages in each of these sections, while the flux ϕ_2 induces canceling voltages. In this manner the two sections 34 and 35 are magnetically isolated from the windings formed by the winding sections 29, 32 and 30, 33.

10 The complete circuit diagram for one form of a coupling unit having a transformer such as described above embodied therein is shown in Fig. 6. In the circuit illustrated the transformer is shown as being embodied in a coupling unit 15 for impressing the output oscillations of an electron discharge amplifier 2' on a load illustrated as a resistance 3'. The respective primary and secondary winding sections 28 to 35 inclusive are shown diagrammatically as being connected in 20 a manner which will produce the desired flux interaction as described in the preceding paragraph. In addition, a pair of circuits are provided for further insuring complete isolation of the respective frequency band transmission 25 channels. One of these circuits comprises a condenser 36 connected in series with the primary winding sections 29 and 30 across the primary winding section 28. A resistance 37 is provided for preventing an undesired lowering of the 30 operable primary winding impedance due to series resonance between the winding sections 29, 30 and 28. Similarly, a resistance 40 is connected in shunt with the sections 34 and 35 for the same purpose. The other circuit comprises a condenser 38 connected in parallel with a resistance 39 in series with the secondary winding sections 32 and 33 across the series connected secondary winding sections 31, 34 and 35.

While the connections shown in Fig. 6, and 40 described in detail hereafter, pertain to a transformer with multi-section windings some of which are effectively paralleled, this is not to be construed as any limitation on the theory of operation of the transformers described in connection with the totally series-connected winding transformers illustrated in Figs. 1 to 4 inclusive. No structural changes in the transformers shown in Fig. 5 and Fig. 14 are involved 45 thereby.

50 The operation of the coupling unit illustrated in Figs. 5 and 6 will best be understood by reference to Figs. 7 to 13 inclusive wherein I have shown the equivalent circuits for the net work of Fig. 6, when particular frequency bands are 55 considered.

For a band of frequencies extending over the lower portion of the operating frequency range the tightly coupled primary and secondary sections 28 and 31 respectively are effective to provide a transmission channel for currents having frequencies within this portion of the operating range. Over the effective transmission range of these two winding sections the condensers 36 and 38 and the resistance 39 together with the 60 high leakage reactance between the respective primary and secondary winding sections effectively isolate the transmitting channels comprising the sections 29, 32 and 30, 33 and prevent these channels from affecting the transmission 65 efficiency of the channel formed by the sections 28 and 31. For currents having frequencies extending over this low portion of the operating frequency range the impedance of the secondary sections 34 and 35 is very low and hence the 70

ratio of voltage transformation is effectively determined by the turn ratio between the sections 28 and 31.

When the range of frequencies referred to in the preceding paragraph is considered, the equivalent circuit for the coupling unit and tube 2' becomes as shown in Fig. 7 wherein e_0 represents the voltage available at the input terminals of the electron discharge device multiplied by the amplification factor of the discharge device, r_p represents the internal anode to cathode resistance of the discharge device 2', R is the equivalent resistance formed by referring the resistance 3' to the primary side of the transformer and X_1 is the primary magnetizing 15 reactance.

At a slightly higher band of frequencies the leakage reactance between the winding sections 28 and 31 becomes appreciable as compared to R and the equivalent circuit becomes as shown 20 in Fig. 8. In this circuit the reactance x_2 represents the leakage reactance between the sections 28 and 31. Over this band of frequencies the primary magnetizing reactance of the transformer becomes so large as to have a negligible 25 effect on the operation of the network and, accordingly, it is omitted from the equivalent circuit shown.

At a still higher band of frequencies the equivalent circuit becomes as shown in Fig. 9 wherein c_1 represents the capacity of the condenser 36, c_2 represents the capacitance of the condenser 38 referred to the primary side of the transformer, the resistance R_1 represents the resistance 37, R_2 represents the resistance 39 referred to the primary side of the transformer, and the reactance x_3 represents the magnetizing reactance of the winding sections 29 and 30. Over this band of frequencies the leakage reactance x_2 is of a magnitude such that the voltage drop 40 therethrough tends to lower the voltage across the terminals of the equivalent resistance R . However, the condensers 36 and 38 become effective over this frequency band to open up the 45 transmission channels 29, 32 and 30, 33 thereby to maintain the desired value of impressed voltage across the terminals of resistance R . It will of course be understood that the turn ratio between the sections 29, 32 and the sections 30, 33 must be the same as the turn ratio between 50 the sections 28, 31 if the voltage across the resistance R is to be maintained at the desired value.

By making the reactance of condenser c_1 approximately equal to x_3 in this portion of the 55 frequency range and further by making R_1 , x_3 , R_2 and x_2 all equal to each other and greater than R , the network will be broadly tuned, thereby increasing the current flowing in x_2 and R by an amount sufficient to compensate for the voltage drop produced by the resistance R_1 . The resistance 37, or in Fig. 9 resistance R_1 , operates to prevent series resonance, between the capacitive reactance of condenser 36, in Fig. 9, c_1 and the inductive reactance x_3 at any frequency. Similarly the resistance 39, or in Fig. 9 resistance R_2 , prevents series resonance between the secondary magnetizing reactance of the winding sections 32 and 33 and the low frequency blocking condenser 38.

At still higher frequencies the magnetizing reactance x_3 of the network shown in Fig. 9 becomes so large as to have practically no effect on the operation of the circuit. Further, capacitive reactance of condenser C_2 , becomes 75

so small with respect to the resistance R_2 that the latter has little effect on the circuit. Thus, the equivalent circuit for a band of frequencies covering this portion of the operating frequency range becomes as shown in Fig. 10. Partial resonance of the network occurs over the band of frequencies which is sufficient to compensate for the voltage drop produced by the resistor R_2 .

At a still higher band of frequencies the equivalent circuit for the coupling unit illustrated in Fig. 6 may be accurately represented by the circuit of Fig. 11 wherein R_3 represents the resistance 40 of Fig. 6, x_4 represents the inductive reactance of the winding sections 34 and 35, C_3 represents the equivalent distributed capacity of the winding sections 28 and 31 referred to the primary windings 29 and 30 and X_5 is the leakage reactance between primary windings 29 and 30 and secondary windings 32 and 33. Within this band of frequencies the equivalent distributed capacity c_3 of the winding section 31 becomes of sufficient magnitude to constitute a considerable load across resistance 3' which tends to reduce the voltage available at the terminals of the resistance 3' or in Fig. 11 R. However, at such frequencies the winding sections 34 and 35 shunted by the resistance 40 maintain the overall impedance of this branch of the equivalent circuit at a value sufficient to prevent the undesired reduction in voltage. If the circuit elements are selected having the correct impedance values, it is possible to obtain the same voltage transfer ratio in this portion of the operating frequency range as is attained in the lower portions of the range.

In the arrangement of Figs. 5 and 6 it is necessary that the distributed capacity of winding 28 be sufficiently low as not to constitute an objectionable load on discharge device 2'.

At the lower portion of the frequency range in which coils 34 and 35 are operative the equivalent inductance x_4 of the winding sections 34 and 35 is substantially equal to the equivalent capacitive reactance corresponding to the distributed capacity of the winding section 31. Thus, the apparent resistance R_3 corresponding to the resistance 40 as viewed from the input terminals of the coupling unit is the impedance which prevents excessive loading of the windings 32 and 33 over this band of frequencies. It becomes apparent from a consideration of this equivalent circuit that the resistances R_1 and R_3 must be large as compared to the resistance R if a uniform response characteristic is to be obtained over a frequency range including the band at present being considered.

When a still higher band of frequencies is considered the equivalent circuit becomes as shown in Fig. 12 since the reactances represented by C_3 and C_2 are now negligible and x_4 extremely high.

At a still higher band of frequencies covering a range extending to the upper limit of the operating frequency range the equivalent circuit becomes as shown in Fig. 13. In this frequency band the distributed capacity of the winding sections 29, 30, 32 and 33 begins to have a loading effect due to the capacitive reactance thereof, which is effectively in shunt to the resistance R . The equivalent capacity representing these components of distributed capacity is represented by the condenser c_4 . At higher frequencies the loading effect of this condensive reactance is increasingly greater until a frequency is reached where this reactance is equal to the leakage inductive reactance x_5 . This frequency

represents the absolute upper frequency limit for the operating range of the structure shown in Fig. 5 and the voltage ratio characteristic falls off rapidly at frequencies above this value.

It has been found that in certain cases the distributed capacity of the winding 28 tends to overload the source at frequencies extending over the upper portion of the operating range. This undesired effect may be overcome by employing the transformer illustrated in Fig. 14 wherein a pair of primary winding sections 41 and 42 are provided in addition to the elements of the transformer illustrated in Fig. 5 these windings being connected as shown in Fig. 15. The sections 41 and 42 are mounted on the outer legs of the transformer core and are connected to be magnetically isolated from the winding sections 29, 30, 32 and 33. They are designed to have a very low distributed capacity and are shunted by a resistor 43 for preventing series resonance effects between the inductance thereof and the equivalent capacitive reactance formed by the distributed capacity of the winding sections 28 and 31. This obviates the necessity of designing winding 28 to have low distributed capacity.

It has been found that a small coupling unit constructed in the manner described above is capable of transmitting electric circuit currents extending over an exceedingly wide band of frequencies as for example, from 20 cycles to 100 kilocycles or even more. By employing the winding section arrangement illustrated and connecting these sections in the manner shown, the respective frequency band transmission channels thus formed may be magnetically isolated thereby to provide a high leakage reactance between the sections included in each channel, without employing a core structure of unduly large size. It will be apparent to those skilled in the art that any number of channels may be provided by an obvious extension of the structural arrangement and circuit connections described in the preceding paragraphs and the band width may be even further extended.

While I have shown a particular embodiment of my invention, it will of course be understood that I do not wish to be limited thereto since many modifications in the structure may be made, and I contemplate by the appended claims to cover all such modifications as fall within the true spirit and scope of my invention.

What I claim as new and desire to secure by Letters Patent of the United States is:

1. A coupling unit for coupling together two electric circuits for the transmission therebetween of alternating currents having component frequencies extending over a wide range, comprising a transformer having a core, sectionalized primary and secondary windings on said core, each of the sections of each of said windings having a resonant frequency different from the resonant frequency of each of the other sections of the same winding and substantially the same as that of one section of the other winding, and means including the inductive coupling between the primary and secondary sections having like resonant frequencies for providing a plurality of channels for transmitting currents having frequencies extending over predetermined portions of said frequency range.

2. A coupling unit for coupling together two electric circuits for the transmission therebetween of alternating currents having component frequencies extending over a wide range, comprising a transformer having a core, sectional-

ized primary and secondary windings on said core, each of the sections of each of said windings having a resonant frequency different from the resonant frequency of each of the other sections of the same winding and substantially the same as that of one section of the other winding, the primary and secondary winding sections having the same resonant frequencies being coupled in close inductive relation thereby to provide a plurality of channels for transmitting currents having frequencies extending over predetermined portions of said frequency range.

3. A coupling unit for coupling together two electric circuits for the transmission therebetween of alternating currents having component frequencies extending over a wide range comprising a transformer having a core, sectionalized primary and secondary windings on said core, each of the sections of each of said windings having a resonant frequency different from the resonant frequency of each of the other sections of the same winding and substantially the same as that of one section of the other winding, the primary and secondary sections having the same resonant frequencies being coupled in close inductive relation thereby to provide a plurality of channels for transmitting current having frequencies extending over predetermined portions of said frequency range, and means to produce relatively large leakage reactance between sections having different resonant frequencies whereby loading of one of said channels due to the low capacity reactance of one of said sections corresponding to another of said channels is prevented.

4. A coupling unit for coupling together two electric circuits for the transmission therebetween of alternating currents having component frequencies extending over a wide range comprising a transformer having a core, sectionalized primary and secondary windings on said core, each of the sections of each of said windings having a resonant frequency different from the resonant frequency of each of the other sections of the same winding and substantially the same as that of one section of the other winding, the primary and secondary sections having the same resonant frequencies being coupled in close inductive relation thereby to provide a plurality of channels for transmitting currents having frequencies extending over predetermined portions of said frequency range and being arranged on said core so that the leakage reactances between sections having different resonant frequencies are sufficient to prevent loading of any one of said channels by the other of said channels, and means for preventing series resonance effects between the respective sections of each of said windings from lowering the transmission efficiency of said transformer for currents having frequencies corresponding to the frequencies at which such resonance effects occur.

5. A coupling unit for coupling together two electric circuits for the transmission therebetween of alternating currents having component frequencies extending over a wide range, comprising a transformer having a core and including sectionalized primary and secondary windings, said primary and secondary windings each including a section having a low resonant frequency and a plurality of sections having successively higher resonant frequencies, said primary and secondary windings sections being coupled together in close inductive relation in the order of their resonant frequencies thereby to provide a

plurality of separate transmission channels each effective over a predetermined portion of said frequency range, and means including a resistance connected in shunt with each of said high resonant frequency sections for preventing series resonance effects between the respective sections of each of said windings from lowering the transmission efficiency of said transformer for currents having frequencies corresponding to the frequencies at which such resonance effects occur.

6. A coupling unit for coupling together two electric circuits for the transmission therebetween of alternating currents having component frequencies extending over a wide range comprising a transformer having a core and including sectionalized primary and secondary windings on said core, said windings each including sections having different resonant frequencies and being inductively coupled to provide a plurality of transmission channels each effective over a predetermined portion of said frequency range, and means for preventing series resonance effects between the respective sections of each of said windings from lowering the transmission efficiency of said transformer for currents having frequencies corresponding to the frequencies at which such resonance effects occur.

7. A coupling unit for coupling together two electric circuits for the transmission therebetween of alternating currents having component frequencies extending over a wide range comprising a transformer having a core, sectionalized primary and secondary windings on said core, said windings each including sections having respectively high and low resonant frequencies, said high resonant frequency primary and secondary sections being inductively coupled to provide a transmission channel effective over the upper portion of said frequency range and said low resonant frequency primary and secondary sections being inductively coupled to provide a transmission channel effective over the lower portion of said frequency range.

8. A coupling unit for coupling together two electric circuits for the transmission therebetween of alternating currents having component frequencies extending over a wide range, comprising a transformer having a core, sectionalized primary and secondary windings on said core, said windings each including sections having respectively high and low resonant frequencies, said high resonant frequency primary and secondary sections being coupled in close inductive relation thereby to provide a transmission channel effective over the upper portion of said frequency range, said low resonant frequency primary and secondary sections being coupled in close inductive relation thereby to provide a transmission channel effective over the lower portion of said frequency range, and means to produce relatively large leakage reactance between said high and low frequency sections whereby loading of said first-named channel by the other of said channels due to the low capacity reactance of said low frequency section in said upper portion of said range is prevented.

9. A coupling unit for coupling together two electric circuits for the transmission therebetween of alternating currents having component frequencies extending over a wide range comprising a transformer having a core, sectionalized primary and secondary windings on said core, said windings each including sections having respectively high and low resonant frequencies, said

- high resonant frequency primary and secondary sections being inductively coupled to provide a transmission channel effective over the upper portion of said frequency range, said low resonant frequency primary and secondary sections being coupled to provide a transmission channel effective over the lower portion of said frequency range, said high and low resonant frequency sections of each of said windings being arranged on said core so that the leakage reactances between said sections are sufficient to prevent loading of one of said channels by the other of said channels, and means for preventing series resonance effects between the respective sections of each of said windings from lowering the transmission efficiency of said transformer for currents having frequencies corresponding to the frequencies at which such resonance effects occur.
10. A coupling unit for coupling together two electric circuits for the transmission therebetween of alternating currents having component frequencies extending over a wide range, comprising a transformer having a core, sectionalized primary and secondary windings on said core, said windings each including sections having respectively high and low resonant frequencies, said high resonant frequency primary and secondary sections being inductively coupled to provide a transmission channel effective over the upper portion of said frequency range and said low resonant frequency primary and secondary sections being coupled to provide a transmission channel effective over the lower portion of said frequency range, said high and low resonant frequency windings being connected to form a
- 5 series resonant circuit of substantially zero impedance at a frequency within said range, and means including resistances connected respectively one in shunt with each of said high resonant frequency sections and having a resistance value equal to the reactance value of the shunted section at the frequency where said series resonance occurs for preventing said series resonance effects from lowering the transmission efficiency of said transformer for currents having frequencies corresponding to the frequencies at which such resonance effects occur.
- 15 10. A coupling unit for coupling together two electric circuits for the transmission therebetween of alternating currents having component frequencies extending over a wide range comprising a core, sectionalized primary and secondary windings on said core, said windings each including sections having respectively high and low resonant frequencies, said high resonant frequency primary and secondary sections being inductively coupled to provide a transmission channel effective over the upper portion of said frequency range, said low resonant frequency primary and secondary sections being inductively coupled to provide a transmission channel effective over the lower portion of said frequency range, and means for preventing series resonance effects between the respective sections of each of said windings from lowering the transmission efficiency of said transformer for currents having frequencies corresponding to the frequencies at which such resonance effects occur.
